UNITED STATES PATENT OFFICE

CHESTER D. MILLER, OF LOS ANGELES, CALIFORNIA, ASSIGNOR TO DONALD L. BENTON,
OF LOS ANGELES, CALIFORNIA

DESIGN FOR A FAUCET

Application filed February 1, 1932. Serial No. 42,688. Term of patent 3½ years.

To all whom it may concern:

Be it known that I, CHESTER D. MILLER, a citizen of the United States, residing at Los Angeles, in the county of Los Angeles and State of California, have invented a new, original, and ornamental Design for a Faucet, of which the following is a specification, reference being had to the accompanying drawings, forming a part thereof,

Figure 1 is a side elevational view of a faucet showing my new design.

Fig. 2 is a bottom plan view thereof.

Fig. 3 is an end elevation thereof, as viewed from the left hand side of Fig. 1 looking toward the right.

I claim:

The ornamental design for a faucet as shown.

Signed at Los Angeles, in the county of Los Angeles and State of California, this 21st day of January, 1932.

CHESTER D. MILLER.
